UNITED STATES PATENT OFFICE.

FREDERICK E. MAYNARD, OF BERKELEY, CALIFORNIA.

DESIGN FOR AN EMBLEM OR SIMILAR ARTICLE.

52,667.

Specification for Design.

Patented Nov. 12, 1918.

Application filed June 9, 1914. Serial No. 844,075. Term of patent 3½ years.

To all whom it may concern:

Be it known that I, FREDERICK E. MAYNARD, a citizen of the United States, residing at Berkeley, in the county of Alameda and State of California, have invented a new, original, and ornamental Design for an Emblem or Similar Article, of which the following is a specification, reference being had to the accompanying drawing, forming part thereof.

Figure 1 is a plan view.

Fig. 2 is an edge view.

The invention resides in the novel configuration of a charm, token, emblem or the like comprising a shank or stem portion simulat-

ing a base ball bat having at one end a substantially oval shaped bowl or body portion simulating a catcher's mit having in its center a figure representing a ball.

I claim:

An ornamental design for an emblem or similar article comprising a stem or shank portion simulating a base ball bat having, at one end, a substantially oval shaped body portion simulating a catcher's mit having on its face a figure representing a ball.

FREDERICK E. MAYNARD.
